UNITED STATES PATENT OFFICE.

CHARLES C. LITTLE, OF SAN JOSE, CALIFORNIA.

CARBURETER.

1,399,353.

Specification of Letters Patent.

Patented Dec. 6, 1921.

Application filed March 19, 1919. Serial No. 283,457.

To all whom it may concern:

Be it known that I, CHARLES C. LITTLE, a citizen of the United States, and resident of San Jose, in the county of Santa Clara and State of California, have invented certain new and useful Improvements in Carbureters, of which the following is a specification.

My invention relates particularly to a type of carbureter adapted for use with heavy fuels.

The objects of my invention are to provide a carbureter of the nature indicated in which means is provided for heating the combustible mixture formed therein and in which a means is provided for so regulating the heating means that it will be sufficient to secure complete vaporization of the mixture at all positions of the throttle and yet not so great at any position of the throttle as to cause decomposition of the fuel.

I also contemplate providing in conjunction with the heating means and its controlling means, a means by which the engine may be started and run at slow speed, and a means for the addition of exhaust gas to the mixture.

A still further object of my invention is to provide a carbureter embodying some or all of the means above set forth that will be economical in construction and operation and efficient in its practical application.

With these and other objects in view, reference is made to the accompanying drawings, in which—

Figure 1 is a longitudinal section through the center of my improved carbureter.

Fig. 2 is a sectional view on line 2—2 of Fig. 1.

Fig. 3 is a sectional view on line 3—3 of Fig. 1.

Fig. 4 is a sectional view on line 4—4 of Fig. 1.

Fig. 5 is a perspective illustration of the heat regulating means.

Fig. 6 is a side elevation of the carbureter showing a means of operating the heat regulating means in conjunction with the throttle.

Fig. 7 is an elevation of a portion of the carbureter at 7—7 of Fig. 6.

Fig. 8 is a modification showing an elevation of a portion of the carbureter showing an adjustable means for operating the

heat regulating means when the said heat regulating means is mounted as two separate members.

Fig. 9 is a longitudinal section through a portion of the carbureter showing means 60 on the mixture conduits for the absorption of heat.

Fig. 10 is a detail sectional view through a portion of the carbureter showing a modification in which the guide member is used 65 without a deflector.

Fig. 11 is a detail sectional view through a portion of the carbureter showing a modification in which the deflector is used without the guide member. 70

Similar characters of reference indicate similar parts throughout the several views.

Referring now more particularly to the drawings, 1 indicates the body of the carbureter having a plurality of conduits 75 2—2^a—2^b passing lengthwise therethrough through the vaporizing chamber 3 thereof, the said vaporizing chamber 3 receiving exhaust gases through inlet 4 and discharging the same through outlet 5. 80

The conduits 2—2^a—2^b are preferably formed with comparatively thin side walls and somewhat extended edge walls as indicated at 6—6^a—6^b, thereby forming long, narrow and deep passages as 7—7^a—7^b—7^c 85 through which the exhaust gases from inlet 4 must travel. At 8 is shown a shaft mounted in body 1 and carrying a member comprising deflector 9 and guide 10. Guide 10 extends substantially the full length of 90 chamber 3 and normally is positioned as in Fig. 3 at which time deflector 9 is normally positioned as shown. Deflector 9 is provided with sides 11 which engage the sides and top of bypass 12 and is open at the 95 top so that a deflecting edge of suitable curvature may be formed at 13, and a means provided for discharging exhaust gases as hereinafter described.

A passage is shown at 14 connecting the 100 chamber 3 with conduit 2^a and controlled by a needle valve 15, whereby a small amount of the heating medium may be introduced into the mixture of fuel and air to act as a diluent thereof and thereby prevent too violent explosions.

The explosive mixture is delivered to the several conduits 2—2^a—2^b by a suitable multi-jet carbureting device in which the several jets 16—16^a—16^b discharge into car- 110

bureting chambers 17—17^a—17^b connected with their respective conduits 2—2^a—2^b, and connected to a source of supply 18. In the present instance I have also included a jet 19 discharging into chamber 20 which communicates with a conduit 21 positioned as shown, the jet 19 being supplied from float chamber 22 with a lighter fuel for starting and operating slowly.

- 10 At 23 is shown a rotary throttle inserted between the discharge outlet 24 and the terminals of the several conduits and having grooves as 25—25^a—25^b—27 formed in its periphery and communicating with the terminals of the said conduits by passages 26—26^a—26^b—26^c. Reference is made to my co-pending application for carbureter, Serial No. 207614, filed Dec. 17, 1917, for a complete disclosure of the type of throttle herein referred to. In the present case the throttle is provided with a groove 27 for controlling the flow of fuel from conduit 21, the same being so formed as to close off said conduit as at 28 when the first conduit 2^a is opened to supply a heavier fuel.

I have also here shown auxiliary air ports 29—29^a—29^b—29^c to each passage 26—26^a—26^b—26^c, the passage of air therethrough being controlled by valves 30—30^a—30^b—30^c operating in conjunction with valve controlling means 31—31^a—31^b—31^c, the latter mechanism being fully disclosed in my co-pending application for carbureter filed March 3, 1919, Serial No. 280,330.

- 35 In this preferred form of my invention the action is as follows. In starting, throttle 23 is turned to bring jet 19 into operation, the required amount of auxiliary air is supplied through port 29^c and the diluted mixture passes through groove 27 to the engine. As the engine speed increases and the throttle 23 is rotated further in the direction indicated by the arrow the edge of groove 27 closes off the suction on jet 19 as indicated at 28, and groove 25^b opens as indicated at 32 thereby bringing jet 16 into action with its heavier fuel.

The action of jets 16—16^a—16^b is the same whether or not a supplementary jet 19 is used for starting with lighter fuel, and is as follows. Upon the opening of groove 27^b jet 16^b is brought into action, the mixture being formed in a chamber 17^b which is small compared to the capacity of the auxiliary valve 30^b. The mixture is drawn through conduit 2^b, the same having a considerably elongated cross-section as shown in Fig. 3, the thin sides of the conduits thereby presenting a greater surface for the absorption of heat than would be the case if a more compact section were used, and the extended end walls 6^b providing more surface for absorption and more mass for the retention of heat. The heating of these parts is effected by concentrating the exhaust gases passing

through chamber 3 upon the walls of conduit 2^b by the positioning of guide 10 as shown, the heated walls assisting materially in the vaporization of the heavy fuel passing therethrough. A further means of extracting and utilizing heat available at low speeds consists in the provision of fins or ribs, as 33, upon the side walls of the conduit 2^b.

A further opening of the throttle brings grooves 27^a and jet 16^a into action and also 75 swings guide 10 into the position indicated at 10^a, and deflector 9 into the position 9^a through the medium of suitable connections such as indicated by the numerals 35 to 40. A portion of the more highly heated gases 80 due to the greater engine speed is now discharged through by-pass 12 and the balance is directed around the first two conduits 2^a and 2^b, conduit 2^a also being provided with a plurality of fins 33 of smaller dimensions, or 85 fewer in number, than those placed on conduit 2^b. With the throttle 23 wide open the guide 10 assumes a position as at 10^b and the deflector opens to 9^b so that a larger proportion of the still more heated gases is discharged at 12 and the balance is allowed to 90 pass around all of the conduits 2—2^a—2^b, conduit 2 not being provided with heat absorbing fins in the present case.

It is apparent, of course, that the capacity 95 of the deflector or valve 9 is determined in part by the form given to its upper unattached edge 13 in conjunction with the edge of the body of the carbureter 1 with which it operates.

As a means for operating this member in conjunction with the throttle 23 I have shown a sector 34^a on link 34 pivoted at 35 and connected to arm 36 of said throttle lever by link 37. The sector 34^a operates a 10 pinion 38 and worm gear 39 which in turn operates a pinion 40 on the shaft 8 of deflector 9 and guide 10. This construction is desirable inasmuch as there is considerable pressure of a pulsating nature in the carbureter, the members being interconnected and irreversible.

In the embodiment shown in Fig. 8 the guide 10 is mounted on a separate shaft 41 having an arm 42, and shaft 8 of deflector 9 has an arm 43, the two arms being connected by a link 44. It is evident that any suitable connection to the throttle will operate the two members 9 and 10 simultaneously in any predetermined relation to each other, the said relation being effected by suitable adjustment of link 44 on arms 42 and 43 by means of pins 45 in adjusting holes 46. By this adjustment the relative degrees of motion between members 9 and 10 can be varied or member 9 can be given a certain amount of lead or lag over member 10.

There may be certain conditions under which either one of the members 9 or 10 may be useful alone in which case they may

be mounted substantially as described in the foregoing description and as illustrated in Figs. 10 and 11 respectively.

It is understood of course that changes in form, construction, operation and general arrangement of the several features may be made within the scope of the appended claims.

I claim:

- 10 1. A combined vaporizer and carbureter including a heating medium conducting chamber having an inlet and outlet, fuel conduits extending through the chamber between the inlet and outlet, a by-pass arranged in the wall of the chamber between the inlet and said conduits and adapted to place the interior of the chamber in communication with the atmosphere, a valve mounted in the by-pass for controlling the passage of heating medium from the chamber to the atmosphere, an adjustable deflector mounted in the chamber for directing heating medium onto one or more of said conduits, and means connecting the valve and deflector, the valve, deflector and means connecting the same being so arranged that opening of the valve will cause the deflector to direct heating medium on an increasing number of conduits.
- 20 2. A combined carbureter and vaporizer of the kind defined by claim 1 in which the valve and deflector are pivotally mounted and in which the deflector extends substantially the entire length of the interior of the chamber.
- 30 3. A combined vaporizer and carbureter including a heating medium conducting chamber having an inlet and an outlet, fuel conduits extending through the chamber between the inlet and outlet, and an adjustable deflector mounted in the chamber between the conduits and inlet for concentrating heating medium on one or more of said conduits.
- 40 4. In a combined vaporizer and carbureter, a heating medium conducting chamber, conduits extending through the chamber, a by-pass positioned in the wall of said chamber, a valve pivotally mounted in said by-pass and having a front member extending into said chamber, said front member having a deflecting edge of such contour as to progressively open said by-pass to deflect heating medium therethrough when opened, and having side members attached to said front member and engaging said by-pass, means for operating said valve, and a deflector mounted in the chamber between the conduits and inlet for concentrating heating medium onto one or more of said conduits.
- 50 5. A combined vaporizer and carbureter including a heating medium conducting chamber having an inlet and an outlet, a plurality of substantially parallel spaced conduits passing through the chamber be-

tween the inlet and outlet, a by-pass arranged in the wall of the chamber, a valve controlling said by-pass, an adjustable deflector operatively connected with said valve and mounted in said chamber between the conduits and inlet and adapted to concentrate a heating medium upon one or more of said conduits, and means for adjusting the deflector and valve.

6. A combined vaporizer and carbureter including a heating medium conducting chamber, a plurality of vaporizing conduits arranged in said chamber, a throttle for controlling the passage of fuel through said conduits, a by-pass positioned in the wall of said chamber, a valve operatively mounted in said by-pass, connections for rendering said throttle and said valve coactive, and means coacting with said valve for concentrating the flow of heating medium around one of said conduits when said valve is closed and around additional conduits as said valve opens.

7. In a combined vaporizer and carbureter, a heating medium conducting chamber, a plurality of vaporizing conduits passing through said chamber, a by-pass positioned in the wall of said chamber near said conduits, a deflector pivotally mounted in said chamber adjacent said conduits and adapted to concentrate the flow of heating medium around one or more of said conduits, and a valve pivotally mounted in said by-pass to coact with said deflector and having side flanges adapted to engage said by-pass, and a front member connecting said side flanges, said front member having a deflecting edge of such contour as to progressively open said by-pass as said deflector is shifted with relation to said conduits to permit the passage of heating medium around additional conduits.

8. In a combined carbureter and vaporizer, a heating medium conducting chamber having an inlet and an outlet, one wall of said chamber being provided with an opening to permit the discharge of heating medium from the interior of the chamber to the atmosphere, a plurality of spaced fuel conducting conduits arranged in said chamber between the inlet and the outlet, a valve controlling said opening, a deflector operatively connected with said valve and arranged to direct the heating medium onto one of said conduits when the valve is closed, said deflector being adapted to direct the heating medium onto an increased number of conduits when the valve is opened, a throttle controlling the passage of fuel through the conduits, and means operatively connecting the throttle with the valve and deflector to cause movements of the throttle to be imparted to the deflector and valve.

Executed this 4th day of March, 1919.

CHARLES C. LITTLE.
